UNITED STATES PATENT OFFICE.

JOSEPH BARIS, OF CHICAGO, ILLINOIS.

GAS-HEATED TAILOR'S IRON.

No. 807,533.

Specification of Letters Patent.

Patented Dec. 19, 1905.

Application filed January 26, 1905. Serial No. 242,742.

To all whom it may concern:

Be it known that I, JOSEPH BARIS, a subject of the Czar of Russia, and a resident of Chicago, in the county of Cook and State of Illinois, have invented certain new and useful Improvements in Gas-Heated Tailors' Irons, of which the following is a full, clear, and exact description.

The object of my invention is to provide an improved gas-heated pressing-iron for tailors in which the ignited gas and the products of combustion generated thereby will thoroughly distribute itself over and heat the bottom plate of the iron and yet be so disposed as to prevent the radiation from the upper surface thereof from burning the hand of the operator manipulating it. This I accomplish by simple and cheap mechanism, substantially as hereinafter fully described, and as particularly pointed out in the claims.

In the drawings, Figure 1 is a side elevation of my improved iron. Fig. 2 is a perspective view of the same, showing it open. Fig. 3 is a vertical central section taken on line 3 3, Fig. 4. Fig. 4 is a vertical transverse section taken on dotted line 4 4, Fig. 3. Fig. 5 is a horizontal section taken on dotted line 5 5, Fig. 3.

Referring to the drawings, A represents the lower section of a sad-iron consisting of a bottom plate of the usual shape and pointed either at one or both ends and having its edges *a* flanged upward to a corresponding extent all around. The upper section of cover B of the iron consists of a top plate of the same dimensions as the bottom plate A and side walls *b*, formed by flanging the edges of the top plate downward, which are almost twice the depth of the flanged edges *a* of said bottom. This upper section B is hinged to one of the flanged side edges of the bottom section, preferably midway its length, and when said upper section is closed over the lower section the edges of the former rest upon the edges of the latter and the two parts can be locked together by means of a dog or hook *c*, which is hinged to the side of the top section of the iron opposite the hinge and engages a suitable stud or pin *c'*, secured to and projecting from the side of the bottom section, substantially as shown in the drawings. The top plate has two bosses *e e* projecting down from its under side in alinement

with the longitudinal vertical plane intersecting the points of the iron, and secured to these bosses by means of screws *e'* passing through its top is an inverted box-shaped air-chamber D. This chamber is of such dimensions that its sides, which are made by flanging the edges of its top plate downward and which are parallel with the side walls of the upper section, are separated from the outer shell of the sad-iron a suitable distance. This air-chamber D is connected with the outer atmosphere by means of suitable air-inlets X, located at the forward and rear ends of said chamber, and permits of a circulation of air such as is necessary for the proper combustion of the gas. The bottom of this chamber D consists of a perforated plate E, which corresponds in design and dimensions to the top of said chamber, and is secured by means of screws *d' d'* to studs *d d*, made integral with and projecting up from the bottom of the lower section of the sad-iron.

Screwed onto and suspended on the end of a pipe F, extending through the center of the top of the upper section of the sad-iron within the chamber D, is an elliptical-shaped drum G, the under convexed surface of which is perforated. This drum is of such dimensions that it does not come in contact with the walls of the air-chamber and is so located that its under side is near the perforated bottom of chamber D when the sad-iron is closed. The upper end of pipe F has suitably connected to it above the top of the iron an elbow *g*, and extending horizontally from this elbow is a nipple K. Nipple K extends past one of the uprights of the handle H of the iron, and this nipple is connected by a suitable flexible tube I to the gas-fixture.

In operation the gas is turned on by properly manipulating a suitable cock or valve J, connected to the outer end of the nipple K, and enters the drum G, and the gas is lighted, preferably when the iron is open. The iron is then closed, and the ignited gas is divided into small jets and flames by being passed through the perforated bottom of the air-chamber and comes in contact with the bottom of the iron, which it thoroughly heats. The products of combustion pass from between the bottom of the air-chamber and the bottom of the iron up between the sides of the air-chamber and the sides of the upper

section of the iron and issue from perforations *k* in the sides of the latter, near the top thereof. The air in the space between the top of the air-chamber and the top of the iron is practically motionless, acts as a non-conductor of the heat, and thus protects the hand of the operator grasping the handle.

What I claim as new is—

1. A self-heating sad-iron comprising a hollow upper section having perforated sides, a hollow lower section hinged thereto, an interiorly-located air-chamber communicating with the outer atmosphere and having a perforate bottom, and a gas-distributer inclosed within said air-chamber and connected with a suitable exteriorly-placed source of fuel-supply.
2. A self-heating sad-iron comprising a hollow upper section having perforated sides, a hollow lower section hinged thereto, an interiorly-located air-chamber held out of contact with the walls of said sections, communicating with the outer atmosphere and having a perforate bottom, and a gas-distributer inclosed within said air-chamber and connected with a suitable exteriorly-placed source of fuel-supply.
3. A self-heating sad-iron comprising a hollow upper section having perforated sides, a hollow lower section hinged thereto, an interiorly-located air-chamber communicating with the outer atmosphere and having a perforate bottom, and a gas-distributer suspended within said air-chamber out of contact with the walls thereof and having perforations in the under side of the same and connected with a suitable exteriorly-placed source of fuel-supply.
4. A self-heating sad-iron comprising a hollow upper section having perforated sides, a hollow lower section hinged thereto, an interiorly-located air-chamber which is held out of contact with the shells of said sections and has a perforate bottom, and a suitable gas-distributer suspended within said air-chamber out of contact with the walls thereof, and which has suitable perforations in the under side thereof, and is connected with a suitable exteriorly-placed source of fuel-supply.
5. A self-heating sad-iron comprising a hollow upper section having perforated sides, a hollow lower section hinged thereto, an interiorly-located air-chamber which is held out of contact with the shells of said sections and has a perforate bottom, a suitable gas-distributer suspended within said air-chamber out of contact with the walls thereof, and which has suitable perforations in the under side thereof, and a suitable exteriorly-placed valve-controlled source of fuel-supply with which said gas-distributer is connected.
6. A self-heating sad-iron comprising a

hollow upper section having perforated sides, a hollow lower section hinged thereto, an air-chamber communicating with the outer atmosphere, and consisting of an upper hollow imperforate portion located within the upper section, and a perforate bottom therefor connected to the lower section, and a gas-distributer inclosed within said air-chamber and connected with a suitable exteriorly-placed source of fuel-supply.

7. A self-heating sad-iron comprising a hollow upper section having perforated sides near its top, a hollow lower section hinged thereto, an air-chamber communicating with the outer atmosphere and consisting of a hollow upper portion inclosed within but out of contact with the shell of said upper section, and a perforate bottom secured to said lower section out of contact with the shell thereof, and a suitable gas-distributer inclosed within said air-chamber and connected with a suitable exteriorly-placed valve-controlled source of fuel-supply.

8. A self-heating sad-iron comprising a hollow upper section having perforated sides, a hollow lower section hinged thereto, an air-chamber communicating with the outer atmosphere, and consisting of an upper hollow imperforate portion located within the upper section, and a perforate bottom therefor connected to the lower section, and a gas-distributer suspended within the upper portion of said air-chamber out of contact with the walls thereof and having perforations in its under side and connected with a suitable exteriorly-placed source of fuel-supply.

9. A self-heating sad-iron comprising a hollow upper section having perforated sides near its top, a hollow lower section hinged thereto, an air-chamber communicating with the outer atmosphere and consisting of a hollow upper portion within but out of contact with the shell of said upper section, and a perforate bottom secured to said lower section out of contact with the shell thereof, and a suitable gas-distributer suspended within the lower portion of said air-chamber out of contact with the walls thereof and having perforations in its under side and connected with a suitable exteriorly-placed source of fuel-supply.

10. A self-heating sad-iron comprising a hollow upper section having perforations in its sides near its top, an imperforate hollow lower section hinged thereto, an interiorly-located air-chamber communicating with the outer atmosphere and consisting of an upper portion located within said upper section out of contact with the shell thereof, and a perforate bottom secured within said lower section out of contact with the walls thereof, and a gas-drum inclosed within the lower portion of said air-chamber and consisting

of a horizontally-disposed flattened hollow member having its under side provided with a suitably - disposed series of perforations, and a vertically - disposed valve-controlled pipe for suspending said drum which extends to the interior of said iron.

5 In testimony whereof I have hereunto set

my hand this 16th day of January, A. D. 1905.

JOSEPH BARIS.
